United States Patent Office

Des. 192,742
Patented May 8, 1962

192,742

CANISTER

Iva Joe Stephens, 708 Kent St., Midland, Tex.

Filed Oct. 3, 1960, Ser. No. 62,346

Term of patent 14 years

(Cl. D44—6)

I claim:

The ornamental design for a canister, as shown.
